UNITED STATES PATENT OFFICE.

CHARLES HAVELOCK TAYLOR, OF MONTREAL, QUEBEC, CANADA.

METER.

1,103,384.

Specification of Letters Patent. Patented July 14, 1914.

Application filed April 5, 1911. Serial No. 619,121.

To all whom it may concern:

Be it known that I, CHARLES HAVELOCK TAYLOR, residing at Montreal, in the Province of Quebec, Dominion of Canada, have 5 invented certain new and useful Improvements in Meters, of which the following is a specification.

My invention relates particularly to fluid meters, and has for its object to provide a 10 meter of this type having an operative member actuated by the fluid being measured and possessing capacity for the maximum flow to be measured and automatically varying with the flow, the function of this member being to operate recording and indicating mechanisms.

The invention may be said to consist of the construction and several combinations and particular arrangement of parts hereinafter described and pointed out in the 20 claims.

For full comprehension however of my invention reference must be had to the accompanying drawings in which similar reference characters indicate the same parts and wherein;

Figure 1 is a vertical sectional view of the meter case with the operating parts partly in elevation and partly in vertical sectional view; Fig. 2 is a horizontal sectional view on line A. A. Fig. 1; Figs. 3 and 4 are horizontal sectional views taken on lines B. B. and C. C. respectively; Fig. 5 is a detail vertical sectional view through a nozzle of the fluid motor and a part of the motor; Fig. 6 is an enlarged detail sectional view of a portion of the motor; Fig. 7 is a detail plan view of a dash-pot; Fig. 8 is an elevation of the part illustrated in Fig. 7; Fig. 9 is a diametrical sectional view of the governor; Fig. 10 is a detail view of a part of the governor; Fig. 11 is a horizontal sectional view on line D. D. Fig. 1 looking down with the piston in its lowermost position; Fig. 12 is a detail horizontal sectional view of a part of the governor; and Fig. 13 is an axial sectional view of the upper end of the piston-rod and the lower end of the indicator case, shown in elevation in Fig. 1.

50 The present embodiment of my invention provides for the passage of the main body of the fluid to be measured through a casing 2 divided, by a cylindrical wall 20 into fluid-receiving and supplying ducts 3 and

4 respectively; the top or cover of this casing having a shallow circular chamber 6 formed therein; and a piston 7 within the cylindrical chamber 20 having its rod 8 projecting upwardly through and slideable in the cover. The cylindrical wall 20 is 55 formed with holes 21 effecting a communication between the ducts 3 and 4 and arranged in a spiral series and increasing progressively in area from the lower to the upper end of the series. The aggregate 65 area of these ports is such that the wall 20 will offer a resistance supplemented by the weight of the piston, establishing when there is a flow, a constant pressure within the duct 3 greater than that in the duct 4 and 70 this difference in pressure is utilized to provide the power to impart a constant movement to a member adapted to actuate the registering mechanism and variable automatically with the flow. This member, indicated at 30, is carried at the upper end 75 of the piston rod 8, and it is of cylindrical form with its perimeter provided with gear teeth 31 of saw-tooth form and disposed parallel to the axis, the upper edge 32 of 80 the cylinder being of helical form and the lower edge 33 circular and at right angles to the axis, the resultant surface progressively decreasing in effective area from the circular end, which is commensurate with 85 the maximum flow, to the helical end terminating in a point bearing one tooth only. Rotary movement is imparted to this member by the fluid being measured, through the medium of a turbine 50 driven by the 90 fluid in duct 3 under the pressure due to the resistance offered by wall 20 and the weight of the piston and the parts sustained by the latter. This operation is effected by the following construction: The lower end of 95 the cylindrical wall 20 is interiorly chambered as at 60 and the continuity of the innerside of the wall is maintained by an annular wall section 61 of wire gauze serving as a strainer to prevent clogging of the 100 chamber. A pair of pipes 62 leads from this chamber to a pair of nozzles 63 preferably cast in a circular cover plate 64 secured, by screws 65 for instance, over the before mentioned chamber 66 which has a 105 central exhaust port 67 communicating with the duct 4. The turbine 50 is located in this chamber and carried on the lower end

of a shaft 70, the nozzles being arranged to project their jets obliquely downwardly and tangentially relatively to the circumferential portion of the upper side of the turbine. This turbine consists of a rim 75 having a series of substantially radial and substantially crescent-shaped buckets 76 inclosed by an outer rim or band 77 adapted to brace the buckets and coact with the rim 75 in forming with the buckets, pockets receiving the impacts of the jets and consequently obtaining maximum efficiency therefrom. A hub 78 and web 79 rigidly connect these parts to the shaft. The upper portion of this shaft has fixed thereon an elongated pinion 80 which intermeshes with a large gear 81 fixed upon the piston rod 8 near the upper end thereof. This arrangement provides a motive fluid by-pass from duct 3 to duct 4 through pipes 62, nozzles 63, the impact chambers between the buckets 76, the turbine chamber 66, exhaust port 67, to the duct 4; and the power developed is transmitted from the turbine through its shaft 70 elongated pinion 80 and gear wheel 81 to the piston rod 8, and consequently the cylindro-helical member 30 and the piston 7.

The cylindro-helical member imparts motion to the registering devices through the medium of a spur gear 100 having saw-teeth and held yieldingly in intermeshing relation with the saw-toothed surface of such member, while a pinion 102 rigidly connected to the gear 100 intermeshes with a gear wheel 103 rigidly mounted on a shaft 105 from which rotary movement is imparted to the registering devices. Before describing the connection between the shaft and these devices, however, I will describe the manner in which the piston rod 8, shafts 70 and 105, and the port wall 20 are mounted and the piston rod is vertically sustained, in this embodiment of my invention.

The port wall 20 rests on the top of a fixed cylindrical wall 200 within the globular lower portion 201 of the casing and having a lateral extension 202 terminating in a flanged coupling port 203 affording a means for effecting a connection with the source of supply of the fluid to be measured, the whole constituting the intake duct 3. This lower end of the port wall and the top of the wall 200 are correspondingly grooved to receive a gasket 205, and the upper end of 20 is flanged as at 206 affording a means of connection with the underside of a floor-plate 210 in which the turbine chamber 66 and port 67 before mentioned, are formed. The piston rod also passes through this floor plate and the opening to accommodate it has fitted therein an elongated sleeve 212 with its lower end reduced slightly in diameter and protruding through the floor-plate, a collar 213 formed on the sleeve and embedded in the upper face of the floor

plate and a nut 214 screwed on the said protruding end clamping the device rigidly in position perpendicular to the plate. The piston rod is centered in this sleeve by short sleeves 215 of bronze or other suitable anti-friction metal located at opposite ends of the latter thus steadyng the piston and its rod and permitting vertical movement and rotation thereof.

The rotation of the piston in the cylindrical port-wall 20 is facilitated and leakage therebetween is prevented, by a flat packing ring 216 rotatably mounted upon the underside of the piston and extending slightly beyond the periphery, the edge thereof being beveled; it being retained loosely by the overlapping heads of a series of retaining screws; and in order to secure minimum leakage when the piston is in its lowermost position the portion of the wall above and contiguous to the annular chamber 60 is inwardly inclined.

The pinions 100 and 102 are carried by a shaft 220 mounted in a bearing frame 221 hinged upon the shaft 105 and yieldingly held in position with the pinion 100 intermeshing with the teeth of the member 30, or prepared to do so, by a bow spring 223 having its fixed end fastened to a dash pot 400 to be presently further alluded to, the movement of such frame being arrested by a stop 225 also carried by the dash pot.

The shaft 70 is supported in a frame consisting of the turbine-chamber cover 64 having preferably cast in one therewith a standard 226 curved in cross-section and diminished toward its upper end which is made to extend horizontally to form a bearing 227 having the upper end of the shaft 70 mounted therein, such-shaft being supported at a point above, but near, the cover plate 64, in a bearing plate 275 forming a part of the governor, an essential part of this meter and hereinafter fully described. This bearing plate is centrally chambered and contains a cup 228 of preferably hardened steel, or other suitable material for the purpose, serving as a raceway for a series of balls 229. The thrust is transmitted from the shaft to these balls through a conical hub 230 sustaining a hub 219 forming a part of the governor, a set-screw 231 effecting the required connection between the hub 219 and shaft.

The shaft 105 is supported in a frame 250 extending laterally from the dash pot 400 and presenting a pair of bearing arms 251 252 carrying the shaft, while the upper end of the latter is braced by a stay 253 extending from the standard 226.

A dome 300, secured to the top of the floor plate 210, covers all the mechanism above the latter, has holes 301, 302, in axial alinement with the piston rod 8 and shaft 105, and carries the dial case 305 containing the usual

planetary gear obtaining its power from shaft 105 through a shaft 306 protruding downwardly through the hole 301 packed as at 299, and a pair of clutch blocks 307, 308 secured upon the contiguous ends of the respective shafts 105 and 306, the block 308 having a pair of clutch-pins 310 straddling the block 307 from which torque is transmitted through the pins, block 308, and shaft 306, from shaft 105 to the planetary gears and registering-dials.

An indicating device is provided from which the volume of fluid passing through the meter can at any time be ascertained at 15 a glance, consisting of a tubular cap 350 having a glazed side 351 having graduations 352 with which coats an indicator rod 353 set in the upper end of the piston rod 8; the joint between the tubes 350 and 351 20 being packed by a packing 360 and a tubular plug 361, a nut 362 serving as a stop to limit the upward movement of the piston rod. In order to permit the piston to rotate freely when its rod comes into contact 25 with the nut 362 as just mentioned, which is likely to occur in the event of the meter being overloaded, a cushion 602 and raceways 600 and 601 containing balls 603 are embedded in the upper side of the hub of 30 gear-wheel 81. It may be noted that the indicator rod has perfectly free movement in the indicator tube.

The mechanism thus far described is sufficient for the operation of both the registering and indicating devices of the meter, but correct readings of the registering dials cannot be obtained without constant speed of the turbine and consequently the fluctuable member 30. The governor before mentioned 40 secures this constancy of operation and is specially designed and constructed to meet the requirements of powerfulness and sensitiveness.

This governor comprises the following 45 elements: The bearing plate 275 before mentioned, having a central boss 500 through which it is secured rigidly to the cover plate 64, by screws 501 for instance, the periphery of the plate having a circumferential flange 502 the circumferential surface of which and of the body of the plate present a smooth face. The hub 219, also before mentioned, having a pair of diametrically 50 oppositely extending arms 504, 505 having 55 their free ends 507 extending tangentially and of horizontal U-form, the end of each leg having a flat spring 508 clamped in a diagonal slit therein by screws 509, these springs carrying weighted brake-heads at 60 their opposite ends and serving as fulcrums therefor. Each brake-head consists of a socket 510 for a brake-shoe 512 of Babbitt metal or the like and slit at its top and bottom sides to receive the radially outer 65 ends of the springs 508 which are clamped

therein by screws 513; and the forward side of the head is increased in thickness to constitute a weight 515. As greater uniformity of action is obtained by causing these brake shoes to act in unison they are yoked together by a rigid link 516; and in order to provide for a fine adjustment a pair of adjustable helical springs 517 are made to resist the radial movement of the weights. A pair of radial arms 518, 519 is clamped upon 70 the shaft 70 and between them and the weights the respective helical springs are connected, the end 520 of arm 519 serving as a thumb-piece to facilitate the adjustment of the arms from one angular position to another, the clamps being, of course, first loosened to permit of this action.

The purpose of the dash pot 400 is to prevent vertical vibration or chattering in relation to the proper movement of the piston and the parts carried thereby. It contains the cylindro-helical member 30, which has a trundle ring 410 similar to the ring 216 and for the purpose of facilitating the movement, both circumferentially and axially, of the member, and during the displacement thereof the fluid escaping through the interstices between the teeth of such member suffices to permit of its gentle movement. This dash pot is secured preferably 85 as at 425 rigidly upon the sleeve 212.

The purpose of the partition or floor plate 210 is to prevent the motive fluid passing through the meter and carrying more or less foreign particles, from coming into contact 90 with the main operating ports within the dome and clogging them, pressure equalizing port 450 being provided however to permit of the dome being flooded with a still body of the motive fluid.

The turbine is separately inclosed for the purpose of preventing heavy eddies in the flowing motive fluid from disturbing the accuracy of its operation.

The purpose of the clutch-blocks 307, 308 100 is to permit the dial-case and planetary gears to be lifted away from the main actuating parts of the meter with the dome when it is desired to inspect the said main parts, and return the dome to position again, without the necessity of disorganizing the operating parts, the blocks being in operative relation immediately the pins 310 straddle the block 307.

Operation: When no fluid is being drawn 110 from duct 4 the piston will rest upon the contracted lower portion of the port wall 20 and with its edge in close proximity to but beneath the lowest port of the helical series and consequently the port of smallest capacity. Under this condition the motive fluid will idly fill the duct 3, chamber 60, pipes 62, the nozzles 63, the turbine chamber 66, port 67, duct 4 and the cylindrical space 120 above the piston within the wall 20, and 130

there will consequently be uniformity of pressure on both sides of the piston the weight thereof and of the parts carried thereby being sustained by the lower end of the wall 20. Immediately the smallest flow is started from the duct 4 a difference in pressure is set up between the ducts 4 and 3 and a flow is started from duct 3 through the by-pass 60, 62, 63, 66 and 67 to duct 4 and jets are projected, from the nozzles, and the turbine and consequently the piston commence to rotate. This rotary motion of the piston facilitates its upward movement, and it uncovers sufficient port-area to 15 accommodate the flow, and as the flow increases or diminishes the fluctuations are followed to the most minute degree by the piston, and the movements up or down according to the amplification or diminution 20 of the flow, and however small, are facilitated and the response of the meter accelerated, by the rotary movement of the piston. The power developed in the turbine depends upon the pressure it is necessary 25 for the motive fluid in duct 3 to exert in lifting and sustaining the weight of the piston and that carried by it. This rotary motion is transmitted from the turbine to the piston through shaft 70 pinion 80 gear 30 wheel 81 and the piston rod 8.

The velocity of the turbine is maintained constantly by the governor the action of which is so controlled that when the velocity reaches a predetermined degree adjusted by the springs 517, the resistance of 35 these springs will be overcome and the brake-shoes 512 bear upon the flange 502, which constitutes a brake-ring, to an extent dependent upon the amount of friction required to retard the shaft and keep the velocity within the necessary bounds to maintain uniformity. This uniform rotation of 40 the piston is transmitted through the piston-rod, the toothed surface of the cylindro-helical member 30, pinions 100 and 102, gear wheel 103, shaft 105, clutch blocks 307, 308, shaft 306, to the planetary gears and the 45 dials.

The pinion 100 remains stationary, in so 50 far as axial displacement is concerned, and when there is no flow through the meter the upper end of the fluctuating member 30, bearing the single tooth, is slightly below the level of the pinion and is consequently 55 free to rotate without touching the pinion, but its position is such that upon the commencement of the piston to rise and uncover the lowermost port, and the motive fluid to flow, the helical end of the member 30 60 will simultaneously assume a position in engagement with the pinion; and as the volume of flow increases and this member rises the operative circumferential area of the latter and the extent of rotation of the pinion increase proportionately, and decrease 65

when the volume decreases, the fluctuations in the flow being in this manner simultaneously transmitted to the registering dials, the accuracy of this registering action being insured by the uniformity of rotation of 70 the turbine.

What I claim is as follows:—

1. In a fluid meter having a passage therethrough the combination with a cylindrical port-wall dividing the passage, a piston within the said wall and controlling the ports therein, an indicating device, and means operatively connecting the piston to the indicating device, of means for rotating the piston. 80

2. In a fluid meter having a passage therethrough the combination with a cylindrical port-wall dividing the passage, a piston within the said wall and controlling the ports therein, an indicating device, and means operatively connecting the piston to the indicating device, of means for rotating the piston and a governor controlling the said last mentioned means. 85

3. In a fluid meter the combination with 90 registering devices, of fluctuating means operatively connected to the registering devices, a piston operated by the fluctuations of fluid passing through the meter, means operatively connecting the piston to the 95 fluctuating means, means for rotating the piston, and a governor controlling the said piston rotating means.

4. In a fluid meter having a passage therethrough the combination with registering devices, a cylindrical port-wall dividing the passage, a piston within the said wall and controlling the ports therein, and a piston-rod carried by the piston, of a cylindro-helical member mounted upon the piston-rod, 100 rotary mechanism stationary relatively to its axial direction and effecting a rotative connection between the said cylindro-helical member and registering devices, and means for rotating the said member. 110

5. In a fluid meter having a passage therethrough the combination with the frame of the meter and registering devices, of a cylindrical port-wall dividing the passage through the meter and having an annular 115 chamber near the lower end thereof, a fluid impact motor, a nozzle arranged to project a jet of motive fluid against the said motor, the frame of the meter having a duct and an exhaust port, the duct leading from the said annular chamber to the nozzle, and the exhaust port leading from the motor to the portion of the passage outside of the port-wall, a shaft carrying the said motor, a piston within the port-wall and controlling the ports therein; a piston rod carried by the piston, means rotatively connecting the said shaft to the piston rod, a governor operatively connected to the said shaft, and variable operative means in rotative relation 120 125 130

with and controlled by the said piston-rod and rotatively connected to the said registering devices.

6. In a fluid meter having a passage there-
5 through the combination with the frame of
the meter and an indicating device, of a cy-
lindrical port-wall dividing the passage and
having an annular chamber near the lower
10 end thereof, a fluid impact motor, a nozzle
arranged to project a jet of motive fluid
against the said motor, the frame of the
meter having a duct and an exhaust port the
duct leading from the said annular cham-
15 ber to the nozzle, and the exhaust port lead-
ing from the motor to the portion of the
passage outside of the port-wall, a shaft
carrying the said motor, a piston within the
port wall and controlling the ports therein,
20 a piston rod carried by the piston, means
rotatively connecting the said shaft to the
piston rod, and an indicator carried by the
piston rod and coacting with the said in-
dicating device.

7. In a fluid meter the combination with
25 registering devices, of a cylindro-helical
member having axial saw-teeth, means
whereby the said member is fluctuated axi-
ally in unison with the fluctuation of the
flow, a saw-toothed pinion in engage-
30 ment with the said member, and means opera-
tively connecting the said pinion to the reg-
istering devices.

8. In a fluid meter the combination with
35 registering devices, of a cylindro-helical
member having axial saw-teeth, means
whereby the said member is fluctuated axi-
ally in unison with the fluctuation of the
flow, a saw-toothed pinion and a spring
40 yieldingly retaining the pinion in engage-
ment with the said member and means opera-
tively connecting the said pinion to the
registering devices.

9. In a fluid meter the combination with
45 a hollow cylindrical member and a member
rotatable within the same, of a trundle ring
mounted rotatably upon the rotatable mem-
ber and running freely upon the interior of
50 the cylindrical member for the purpose of
facilitating the movement of the rotatable
member and affording an effective packing
between said rotatable member and the cy-
lindrical member.

10. In a fluid meter the combination with
55 registering devices, of a dash pot, a cylin-
dro-helical member within the dash pot, a
trundle ring mounted rotatably upon the
inner end of the member and running freely
upon the interior of the dash pot for the

purpose of facilitating the rotation; means
whereby the said member is fluctuated axi-
ally in unison with the fluctuations of the
flow, and means operatively connecting the
said member to the registering devices.

11. In a fluid meter having a passage
therethrough the combination with a cylin-
drical port-wall dividing the passage, a pis-
ton within the said wall and controlling the
ports therein, an indicating device, and
means operatively connecting the piston to
the indicating device, of a trundle ring
70 mounted rotatably upon the piston and run-
ning freely upon the cylindrical port-wall,
for the purpose of facilitating the rotation
of the piston and means for rotating the
piston.

12. In a fluid meter having a passage
therethrough, the combination with the
frame of the meter and registering devices,
of a cylindrical port-wall dividing the pas-
sage and having an annular chamber near 80
the lower end thereof, a fluid impact motor,
a nozzle arranged to project a jet of motive
fluid against the said motor, the frame of
the meter having a duct and an exhaust port,
the duct leading from the said annular 85
chamber to the nozzle and the exhaust port
leading from the motor to the portion of the
passage outside of the port-wall, a shaft car-
rying the said motor, a piston within the
port-wall and controlling the ports therein;
90 a piston rod carried by the piston; variable
operative means in rotative relation with
and controlled by the said piston-rod and
rotatively connected to the said registering
devices; means rotatively connecting the 95
said shaft to the piston rod, a governor op-
eratively connected to the said shaft and
comprising a member having a cylindrical
face, a hub mounted rigidly upon the said
shaft and having a pair of diametrically 100
oppositely extending arms, a pair of brake
heads, flat-springs supporting the brake
heads upon the outer ends of the arms in
bearing relation with the said cylindrical
face, adjustable means yieldingly retaining 105
the brake-heads against movement relatively
to the cylindrical face, and means opera-
tively connecting the brake-heads together
to move in unison.

In testimony whereof I have signed my 110
name to this specification in the presence of
two witnesses.

CHARLES HAVELOCK TAYLOR.
